BLADE MAGAZINE

Meyer J. Shnitzler, Brookline, Michael D. Benedict, Jr., Lynn, Ralph Abrams, Roxbury, and James C. Flynn, Belmont, Mass., assignors to The Gillette Company, a corporation of Delaware

Application April 2, 1949, Serial No. 85,206

4 Claims. (Cl. 30—40)

1

This invention comprises a new and improved magazine for safety razor blades, more especially that type of magazine in which a supply of blades is maintained in stacked formation arranged to be ejected one after another as required by the user.

The principal object of the invention is to provide a magazine which may be constructed at little or moderate cost and which at the same time will contain an ample supply of blades, safeguarded against edge contact but so arranged that a single blade at a time may be separated from the stack and ejected without danger of jamming or of cutting the user's fingers.

The invention is herein shown as embodied in a magazine of the injector or repeater type wherein the separate blades are ejected by reciprocation of a feed slide that may be readily operated by the user and, when so operated, automatically and accurately effects the desired separating and ejecting operations.

In one aspect, the magazine of our invention comprises a channel-shaped casing having grooved side walls and a sheet metal cover fitting slidably in the grooves of the side walls and having angular portions at both ends positively locking the cover against movement in either direction longitudinally with respect to the casing. A magazine of this character has the outstanding advantage that it may be constructed essentially of two parts, a casing and a cover, and that these parts may be interlocked in assembled relation without requiring other fastening means.

Going more into detail, the magazine of our invention in its preferred form comprises a channel-shaped casing, which may be formed advantageously by molding plastic material, and a sheet metal cover which as herein shown is shaped to fit slidably into the grooves of the casing and is provided with angular portions that interlock with the casing and hold the casing and cover positively in assembled relation. Preferably, the interlocking portion at one end of the cover is fully shaped before the parts are assembled, while the locking portion at the other end of the cover is arranged to be bent into its interlocking position after the magazine has been filled with blades and the cover assembled in position upon the casing.

These and other features of the invention will be best understood and appreciated from the following description of a preferred embodiment thereof, selected for purposes of illustration and shown in the accompanying drawings, in which:

2

Fig. 1 is a view in perspective of the blade magazine, shown on an enlarged scale;

Fig. 2 is a fragmentary view of the blank from which the cover is formed;

Fig. 3 is a view in perspective of the magazine parts shown in exploded relation; and

Fig. 4 is a view of the magazine in cross-section.

Fig. 5 is a fragmentary view in perspective of the rear end of the casing.

10 The magazine in its illustrated form comprises an elongated rectangular casing having a bottom 10, externally corrugated side walls 11 and 12, a front end wall 13 and a rear end wall 14. The casing may be advantageously molded from any suitable plastic material such as cellulose acetate, Vinylite, Bakelite, or the like. The side walls are parallel and define a channel of uniform width from end to end of the casing. They are provided internally with opposed longitudinal 15 grooves adjacent to their rounded upper edges, and these grooves are open at opposite ends of the casing. In the bottom 10 is provided an inwardly-inclined guideway or ramp 15 which terminates in a transverse slot 16 opening into the bottom of the casing. The guideway 15 is located in the rear portion of the bottom 10, and the slot 16 opens into a rectangular well 17 formed in the inner face of the bottom for the accommodation of a bowed spring 18 which is best shown in Fig. 3. It will be understood that after the magazine has been filled and closed, the bowed spring may be advanced along the guideway 15, passed through the slot 16 and located in the well 17 beneath a stack of blades which has already been placed in the magazine.

15 The side wall 11 of the casing is cut away or shaped at its forward end to form a vertical external shoulder 19, which defines a recess 20 in the wall. The shoulder 19 extends into the bottom of the casing, providing an elongated notch 40 therein.

20 Within the casing is provided a pair of vertical posts 21 and 22, and these posts present divergent vertical walls which engage correspondingly beveled corners of the blades and thus hold the blades in spaced relation from the inner face of the wall 12. In this way the sharp edges of the blades are guarded against contact with any part of the magazine. The 45 rear end wall 14 of the casing is provided with exterior notches 23 in its upper corners, and these notches are defined in part by inwardly and upwardly inclined edge surfaces.

25 The casing member has now been fully described, and it will be apparent that it can be

formed advantageously by injection molding and that it is adapted for straight draft from the molds with the exception of the longitudinal grooves in its side walls. The formation of these grooves, however, requires only the presence of contractible core members in the mold, these being well known in the molding art.

The cover member may be formed advantageously from a single flat blank of sheet steel or other metal. As suggested by the fragmentary view of Fig. 2, it comprises an elongated rectangular body portion 24 provided with a longitudinal median slot 25 for the feed slide and having at its rear end a pair of laterally extending tongues 26 formed by opposed transverse slots. The body 24 and the tongues 26 are of such width as to fit slidably but snugly into the opposed grooves of the side walls of the casing. At its forward end the cover is provided with an angular wall portion 27 extending downwardly at right angles to the body 24 and of such dimensions as to completely fill the recess 20 formed in the forward end of the wall 11. At its lower end the angular portion 27 is provided with an in-turned flange 28 which is shaped to fill the elongated notch in the bottom 10 beneath the recess 20. The angular portion 27 merges into a forwardly or outwardly extending key or pilot 29 which in using the magazine with a safety razor serves to establish and maintain the magazine and razor in operative relation for blade transfer. It will be apparent that the cover member above described may be formed readily from the flat blank partially shown in Fig. 2 by bending the portions 27 and 28 into the desired position with respect to the body 24 and that the angular wall portion 27 when fitted into its recess 20 will firmly support the forwardly extending pilot 29.

The feed slide, comprising an outer member 30 and an inner member 31 connected to the slide by a tongue 32, is mounted on the body 24 of the cover for reciprocating movement longitudinally of the magazine. One form of blade 33 adapted to be supplied by the magazine above described is shown in Fig. 3. It will be noted that the two corners of the sharpened edge of the blade are beveled at an angle corresponding to that of the inclined faces of the posts 21 and 22 of the magazine casing. It will be noted also that the front end wall 13 of the casing terminates slightly below the opposed grooves in the side walls of the casing and thus define an exit slit at that end of the magazine.

In practice a stack of blades 33, for example ten or twenty blades, is placed within the casing and properly located in the forward end thereof by the inclined faces of the posts 21 and 22 with their rear unsharpened edges approximately in contact with the inner face of the wall 11. The cover may now be slipped rearwardly into the opposed grooves of the side walls and moved rearwardly until the angular side portion 27 of the cover is fully seated in the recess 20 and in contact with the shoulder 19 shown in Fig. 1. When the cover is thus assembled, the ears 26 are brought into registration with the notches 23 in the rear wall. The cover may now be positively interlocked with the casing by bending down the ears 26 into the notches 23 as shown in Fig. 1. The cover is thus positively interlocked at both ends with the casing being held against rearward movement by the shoulder 19 and against forward movement by the bent ears 26. At this stage, the feed slide is free to reciprocate idly.

upon the cover 24. The loaded magazine is now inverted and the spring 18 inserted through the guideway 15 and the slot 16, as already described. When fully seated in the well 17, the spring 18 bears symmetrically on the blade stack and holds the uppermost blade thereof yieldingly in contact with the inner face of the body 24 of the cover. Accordingly, when the feed slide is moved to its extreme rear position beyond the post 21 it passes behind the end of the uppermost blade in the stack. Subsequently, when the feed slide is moved forwardly, it engages the uppermost blade and advances it out through the blade exit slit as suggested in Fig. 1. In practice, this ejecting movement will transfer the blade directly to the blade seat of the safety razor which, though not herein shown, will at that time be properly positioned by the finger 29 for the blade-transferring operation.

As an optional feature, the wall 11 is shown as provided in its upper edge with a deep notch 34 extending substantially below the body 24 of the cover and thus serving as a sight window. Through this window the rear unsharpened edges of the blades 33 in the magazine are visible and consequently the user may at any time ascertain the condition of his supply of blades.

Having thus disclosed our invention and described in detail one illustrative embodiment thereof, we claim as new and desire to secure by Letters Patent:

1. A blade magazine comprising an elongated channel-shaped plastic casing with parallel side walls having opposed grooves and end walls, one of the end walls being recessed at an upper corner, one side wall having an open cut-away portion at its end opposite to the recessed end wall, and a sheet metal cover fitting at its edges in said grooves and having at one end an ear bent into the recess of said end wall and at the other end an angular section bent into the open cut-away portion in the side wall of the casing, thus positively holding the cover against longitudinal displacement in either direction on the casing.

2. A blade magazine including in its structure a channel-shaped plastic casing with a bottom, end walls and grooved parallel side walls, one end wall being recessed and the other defining in part the blade-exit opening of the magazine, and one side wall and the bottom having a cut-away portion at the end of the magazine opposite to the recessed end wall, and a sheet metal cover fitting in the grooves of said side walls and having at one end an ear bent into the recess of the end wall and at the other an angular section fitting the cut-away portion at the other end of the casing in the side wall and bottom thereof and an elongated finger projecting outwardly therefrom beyond the end of the casing.

3. A blade magazine comprising a channel-shaped casing having grooved side walls one of which presents a vertically extending shoulder, an end wall recessed in its upper corners, and a flat sheet metal cover fitted into said grooves and having transversely slotted tongues at one end that are bent into the recesses of the end wall and a down-turned portion near its other end disposed in contact with said vertically extending shoulder.

4. A blade magazine comprising a rectangular casing having internal shoulders defining in part a blade-receiving chamber and a bottom, the bottom having an inwardly and upwardly inclined guideway therein terminating at its inner end in a transverse slot opening into the said

blade-receiving chamber and a bowed spring therein which is narrower than the guideway whereby it may be introduced through the transverse slot and guided into the blade-receiving chamber beneath a stack of blades therein.
